UNITED STATES PATENT OFFICE

150,535

DESIGN FOR A CHAIR BACK

Chester J. Barecki, Grand Rapids, Mich., assignor
to American Seating Company, Grand Rapids,
Mich., a corporation of New Jersey

Application March 8, 1947, Serial No. 137,465

Term of patent 14 years

(Cl. D15—8)

To all whom it may concern:

Be it known that I, Chester J. Barecki, a citizen of the United States, residing at Grand Rapids, in the county of Kent and State of Michigan, have invented a new, original, and ornamental Design for a Chair Back, of which the following is a specification, reference being had to the accompanying drawing, forming a part thereof.

Figure 1 is a perspective view of a chair back showing my new design, the dotted lines being for illustrative purposes only;

I claim:

The ornamental design for a chair back, substantially as shown and described.

CHESTER J. BARECKI.
